UNITED STATES PATENT OFFICE

2,101,284

LIFESAVING CHUTE

Lewis Simpson, Monterey Park, Calif.

Application October 19, 1935, Serial No. 45,824

1 Claim. (Cl. 227—39)

This invention relates to a life saving chute, the general object of the invention being to provide an elongated chute made of canvas or the like and means for connecting one end of the chute adjacent a window or the like of a building or to a part of a boat whereby persons can descend through the chute to the ground or other point of safety, with means whereby the persons, or another person can regulate the descent through the chute.

This invention also consists in certain other features of construction and in the combination and arrangement of several parts, to be herein-after fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation showing the device in use.

Figure 2 is a top plan view of the lower end 25 of the device.

Figure 3 is a section on the line 3—3 of Figure 1.

Figure 4 is a longitudinal sectional view through the device, the section being taken on the line 30 4—4 of Figure 5.

Figure 5 is a top plan view of the device.

Figure 6 is a section on the line 6—6 of Figure 5.

Figure 7 is a fragmentary elevation showing 35 how the reinforcing rope is connected with the chute.

Figure 8 is a fragmentary longitudinal sectional view showing the brake means.

Figure 9 is a section on the line 9—9 of Figure 40 8.

Figure 10 is a view of the metal plate to which the brake means are connected.

In these views the numeral 1 indicates an elongated chute made of canvas or the like and of 45 circular shape in cross section and having a hoop 2 at each end thereof. Hooks 3 are connected to the upper end of the chute by passing through holes in the hoop and the hem which encloses the upper hoop and these hooks are 50 adapted to be placed over objects in a room, a part of a window or the like or part of a boat for holding the upper end of the chute in position where a person can enter the same. Ropes 4 pass through longitudinal extending casings 5 formed on the chute and at the sides thereof

and these ropes have their upper ends projecting so that they can be used for fastening the upper end of the chute in position. These ropes are also connected to the upper hoop by the staples 5. A substantially semi-circular apron 5 is connected with the lower end of the chute and forms an extension of the bottom part thereof so that a person passing from the chute will pass over the apron and said apron is provided with the loops 7 which form hand holds so persons can hold the chute in the position shown in Figure 1 or in position leading persons from a boat to a small boat or the like and these loops can be fastened to stakes or the like to hold the device in position. The lower ends of the 10 ropes 4 are also extended as shown at 4' so that these ropes can be fastened to objects upon the ground or in a boat or the like to help hold the device in position.

Upper and lower pulleys 8 are suitably connected with the upper and lower ends of the chute, preferably by being suitably connected to the hoops 2 and an endless cable 9 passes over these pulleys with one portion within the chute and the other portion exterior of the chute. The 20 exterior part of the rope passes through upper and lower brake means 10 preferably attached to parts of the chute by the forked plates 11, one of which is shown in Figure 10, the space between the prongs of each plate receiving the 25 pulley. Each brake member includes a pair of elongated substantially semi-circular members 10', one of which is connected by the plate 11 to a part of the chute and the two members are 30 pivotally connected together at one end as shown at 10''. Each member has a lining 12 of asbestos. Thus by pressing the two members together the linings will grip the cable and thus 35 check movement of the same so that the descent of the person passing downwardly through the 40 chute can be regulated.

It will of course be understood that the device can be used in various ways and in various situations and the descent of a person passing through the chute can be regulated either by a 45 person on the ground or in a boat operating the lower brake or one at the upper end of the device operating the upper brake. If a person is unconscious a fireman or other person can use the device while holding the unconscious person 50 in his arms.

It is thought from the foregoing description that the advantages and novel features of the invention will be readily apparent.

It is to be understood that changes may be 55

made in the construction and in the combination and arrangement of the several parts, provided that such changes fall within the scope of the appended claim.

5 What is claimed is:—

A life saving apparatus comprising an elongated flexible chute having anchoring means at the ends thereof, an elongated endless cable disposed longitudinally of the chute and having 10 one flight externally disposed of the chute and the other flight internally disposed in the chute, pulleys mounted on the end portions of the chute for supporting the said endless cable, a brake

structure at one end of the chute with which the cable is engaged, said brake consisting of a semi-cylindrical shaped structure secured to the chute and provided with upstanding guide walls, and a semi-cylindrical shaped movable member 5 for disposition over the first-mentioned semi-cylindrical structure and between the said guide walls, said semi-cylindrical structures each being lined with a heat resisting material between which the outer flight of the endless cable is 10 disposed.

LEWIS SIMPSON.
